UNITED STATES PATENT OFFICE.

JAMES H. HUFFORD, OF HARTFORD CITY, INDIANA.

FENCE.

SPECIFICATION forming part of Letters Patent No. 248,320, dated October 18, 1881.

Application filed July 1, 1881. (No model.)

To all whom it may concern:

Be it known that I, JAMES H. HUFFORD, of Hartford City, county of Blackford, and State of Indiana, have invented a new Improvement 5 in Fences, of which the following is a specification.

My invention relates to improvements in fences of that class which may be made portable or stationary; and the objects of my invention are, first, to construct a cheap, portable, or stationary fence without the use of posts; second, to connect the panels of fence together by bolts passing through the overlapping edges at the ends of each panel; third, to arrange a 15 fence so that a panel may be easily and quickly taken out when desired. I attain these objects by the mechanism illustrated in the accompanying drawings, in which—

Figure 1 is a perspective view of my fence. 20 Fig. 2 is a top view of the same. Fig. 3 is a cross-section view.

Similar letters refer to similar parts throughout the several views.

Each panel consists of four (more or less) 25 longitudinal boards, five uprights, two foot-braces, and two inclined braces, as shown in Fig. 1. The foot-brace *a* is attached to the lower ends of the boards *d* and *e'* at the ends of the panels, or to the lower end of the slats *i* at the middle of the panels, the other end of 30 which is attached to the lower end of the inclined brace *b*, as shown in all of the figures. The upper end of the brace *b* is notched and fitted up against the board *c* and uprights *d* and *i*, to prevent the fence from leaning or be-

ing blown over. At the ends of the longitudinal boards *c* are connected the upright boards *d*, *e*, and *e'*, as shown in Figs. 1 and 2, and the middle of the said boards are braced by the uprights *i*, as shown. Each end of the panels 40 is provided with narrow boards *e* and *e'*, and one end is also provided with broad board *d*, as shown. The said board *d* overlaps the board *e*, and the ends of the boards *c* of the adjoining panel, and the two boards *e* and *e'* fit together and form a neat connection, as shown in Figs. 1 and 2. Just below the upper board of the panel and through the boards *d* and *e* the bolts *o* pass, as shown in Fig. 1. These bolts are provided with thumb or square taps, 50 as shown. By the construction as described a fence is made portable or stationary, and one that will present a neat appearance.

I am aware that bolts and foot-braces have been used in a similar way. Therefore I do not 55 claim it, broadly; but

What I do claim, and desire to secure by Letters Patent, is—

A series of fence-panels consisting of the horizontal board *c*, the central upright, *i*, the 60 end uprights, *e e'*, and the overlapping upright *d*, provided with bolt-holes and the bolts *h*, whereby the adjoining panels are secured together, substantially as and for the purpose set forth.

JAMES H. HUFFORD.
